UNITED STATES PATENT OFFICE.

HARRY G. ALDRIDGE, OF ROCHESTER, NEW YORK, ASSIGNOR TO HUTHER BROS. SAW MFG. CO., INC., OF ROCHESTER, NEW YORK, A CORPORATION OF NEW YORK.

CUTTER HEAD.

Application filed March 23, 1922. Serial No. 545,953.

To all whom it may concern:

Be it known that I, HARRY G. ALDRIDGE, of Rochester, in the county of Monroe and State of New York, have invented certain new and useful Improvements in Cutter Heads; and I do hereby declare the following to be a full, clear, and exact description of the same, reference being had to the accompanying drawing, forming a part of this specification, and to the reference numerals marked thereon.

My present invention relates to wood-working machinery, and more particularly to rotary tools and cutter heads, and it has for its object to provide a cutter head of this nature that will be strong and serviceable and simple to manufacture and assemble. The improvements are directed more particularly to the mounting of the cutter blades or knives in such manner that they will be securely held accurately in position and yet be readily adjustable to compensate for wear and to regulate the chip. To these and other ends the invention consists in certain improvements and combinations of parts, all as will be hereinafter more fully described, the novel features being pointed out in the claims at the end of the specification.

30 In the drawings:

Figure 1 is a front view of a cutter head constructed in accordance with and illustrating one embodiment of my invention;

Figure 2 is a section therethrough on the line 2—2 of Figure 1;

Figure 3 is an axial section; and

Figure 4 is a perspective view of one of the knives or cutters.

Similar reference numerals throughout the several views indicate the same parts.

In the practice of my invention I provide a cylindrical steel head or body portion centrally bored to fit a spindle 2 on which it is clamped as usual. Though the head may be made with a single or any number of cutters, I have shown two in the present instance oppositely arranged. They are flat and substantially rectangular in shape, as shown at 3 in Figure 4, and are provided with a substantially central elongated slot 4. The head 1 has a sawed or milled slot 5 therein cut on a chord of the circumference so that it opens on both ends but at only one point on the periphery, the slot being cut about two-thirds of the way

through. The knife or cutter 3 fits the slot snugly with its cutting edge 6 projecting from the periphery and its side edges projecting slightly at the end faces of the head, as shown in Figure 3. These projecting side portions are received in and both clamped and guided by ways or channels 7 cut in a pair of end plates 8 that are clamped to the end faces of the head 1 by the collars 9 and nut 10 usually employed for mounting a cutter of this kind on its spindle.

Through a well 11 in the periphery of the head that communicates with the slot 5, a clamping screw 12 is inserted, beneath the head 13 of which the blade or knife 3 is clamped against retrograde movement in the slot and ways, this screw passing through the elongated slot 4 in the knife. Behind the latter in the plane of the slot 5 the head is bored and threaded at 14 to receive a set screw 15 by means of which the blade may be adjusted when the screw 12 is loosened to project its cutting edge 6 the desired distance.

The end plates 8 and their ways 7 fit the head and the blades tightly and may be made to clamp as well as guide the blades, but if the fit is accurate the screws 12 are sufficient clamping means inasmuch as the blade is backed up by the set screw 15 and lateral or twisting movement is absolutely prevented by the plates.

A set screw 16 in a threaded radial bore 17 in the head locks it to the spindle 2.

I claim as my invention:

1. In a cutter, the combination with a cylindrical head having slots therein lying in chords of the circumference, of knives occupying the slots and separate end plates clamped to the head and provided with channels in which the sides of the knives are seated.

2. In a cutter, the combination with a cylindrical head having slots therein lying in chords of the circumference, of knives occupying the slots, separate end plates clamped to the head and provided with channels in which the sides of the knives are seated and are adapted to slide, a securing device for each knife extending transversely through each slot and an adjusting device for each blade arranged in the plane of the slot and adapted to force the blade along the channels.

HARRY G. ALDRIDGE.
